UNITED STATES PATENT OFFICE

MARION F. GOODWIN, OF BAMBERG, SOUTH CAROLINA

TELLURIAN

Application filed September 10, 1930. Serial No. 481,060.

My invention relates to improvements in tellurians.

In accordance with my invention, means are provided to rotate the earth in its orbit around the sun, while maintaining the axis of the earth at the proper inclination, thereby illustrating the action of the rays of light from the sun upon the earth, during different months and seasons. Means are also provided to rotate the earth upon its axis during its travel in its orbit about the sun. Means are provided to move the moon in its orbit about the earth, for illustrating the action of the light from the sun upon the moon, and upon the earth, showing the appearance of the moon through its various phases or changes and illustrating the eclipse of the moon. Means are provided to adjust the support for the moon, for regulating the inclination of the orbit of the moon, for reproducing the travel of the moon as accurately as possible, thereby reproducing an eclipse at any selected time.

In the accompanying drawings, forming a part of this specification, and in which like numerals are employed to designate like parts throughout the same,

Figure 1 is a perspective view of a tellurian embodying my invention,

Figure 2 is a side elevation of the same, Figure 3 is a central vertical longitudinal section through the machine.

Figure 4 is a horizontal section taken on line 4—4 of Figure 3,

Figure 5 is a transverse vertical section taken on line 5—5 of Figure 3,

Figure 6 is a horizontal section taken on line 6—6 of Figure 3,

Figure 7 is a similar view taken on line 7—7 of Figure 3,

Figure 8 is a horizontal section taken on line 8—8 of Figure 3,

Figure 9 is a horizontal section taken on line 9—9 of Figure 3,

Figure 10 is a horizontal section taken on line 10—10 of Figure 3.

In the drawings, wherein for the purpose of illustration, is shown a preferred embodiment of my invention, the numeral 20 designates a horizontal support, which may be in

the form of a table top or other flat surface. This table top is provided with a bearing 21, receiving a preferably tubular vertical shaft 22, provided above the bearing with a ring 23 clamped to the shaft 22 by any suitable means. Arranged beneath the table top is a horizontal bevel gear 24, rigidly attached to the vertical shaft 22 for rotating the same, and this bevel gear is engaged and driven by a bevel gear 25, rigidly mounted upon a horizontal shaft 26, journaled in bearings 27. The shaft 26 is equipped with a crank 28, Figure 1, for turning the same. Means are thus shown to manually rotate the vertical shaft 22, but it is, of course, understood that this vertical shaft may be driven by power or by any suitable means.

The vertical shaft 22 is provided near its upper end with openings 29, receiving the reduced end 30 of a horizontal radial shaft 31, having a shoulder 32. The reduced end 30 is screw-threaded for receiving a nut 33.

The source of light for the apparatus is preferably in the form of an electric lamp 34, embodying the usual electric bulb and reflector for projecting light upon the earth, as will be described. The electric lamp 34 is mounted upon an upstanding rod 35, the upper portion of which is laterally offset, so that the source of light may be spaced a suitable distance from the earth and will not obstruct a proper view of the earth. The lower end of the upstanding rod 35 is provided with a flattened portion 36, having a vertical slot 37, to receive the reduced end 30. This flattened portion 36 is arranged between the nut 33 and a washer 38, and may be rigidly clamped to the shaft 31 by screwing up the nut 33. The source of light thus rotates with the vertical shaft, which is desirable when a source of light having a reflector is employed, so that the light will be properly projected upon the earth. Of course, the source of light could be suspended from the ceiling or the like, and an ordinary electric bulb might be employed with some degree of success.

By embodying a source of light having a reflector projecting the rays in one direction, and traveling

with the vertical shaft, the effect of the relatively stationary sun is obtainable.

Mounted upon the table top 20 is a stationary gear or rack 39, surrounding the vertical shaft 22. This gear has inwardly projecting lugs 39^a which are rigidly attached to the table top 20 by bolts 40 or the like. The stationary gear 39 is slightly elliptical, corresponding to the shape of the orbit of the earth, the vertical shaft 22 representing the location of the sun. The numeral 41 designates a carriage, which is disposed radially of the stationary orbit gear 39. This carriage may be of any well known or preferred construction, and embodies a frame 42 mounted upon wheels or casters 43, traveling upon the table top. Any other suitable form of rolling means may be employed. Rigidly attached to the upper and lower ends of the frame 42 are relatively heavy metal plates 44 and 45. The numeral 46 designates a socket slidably receiving the outer end of the radial shaft 31. This socket has outwardly diverging arms 47, preferably integral therewith, and the ends of these arms are rigidly attached to the lower plate 45 by bolts 48. The socket 46 is capable of moving longitudinally upon the shaft 31, but can not partake of lateral movement with relation thereto. A suitably stiff retractile coil spring 49 is attached to one arm 47 and to the shaft 22. The function of the slidable socket 46 and spring 49 is to retain the carriage in a proper close relation to the stationary orbit gear 38 as it travels about the same, which orbit gear is elliptical, as stated.

The numeral 50 designates a vertical rotary shaft, journaled in a bearing carried by the plate 45 and extending above and below this plate. The shaft 50 has a gear 51 rigidly mounted thereon, see Figures 3 and 4, and this gear permanently engages the stationary orbit gear 38. The permanent engagement is maintained by the self-adjusting longitudinally extensible connection afforded by the shaft 31 and socket 46. At its upper end, the shaft 50 has a gear 52, rigidly mounted thereon, engaging a gear 53, which is arranged between the plates 44 and 45. The gear 53 is rigidly mounted upon a vertical shaft 54, journaled in bearings formed upon the plates 44 and 45. This shaft is disposed centrally of the carriage 41 and the carriage top 55, and projects upwardly beyond the carriage top. The ratio between the gears 51 and 39 is the same as between the gears 52 and 53. The ratio between the gears 51 and 39 may be 3—9, and between the gears 52 and 53, 1—3. The gear 51 is turned upon its axis of rotation in one direction by virtue of its travel about the orbit gear 39, and the gear 53, through the medium of the intermediate gear 52, is rotated in an opposite direction to the gear 51, and as the ratio between the gears in the two sets is the same,

as explained, the result is that a support carried by the vertical shaft 54 will have its longitudinal axis maintained in a fixed position with relation to due north and south.

The top or platform 55 is, of course, rigidly mounted upon the carriage 41, and has its periphery divided into twelve segments 56, having designations indicating the months of the year and the days of each month. The names of the months appear upon the top of the segments, while a scale 57 is formed upon the edge of each segment embodying lines and numerals, as shown. Each vertical line in the scale represents the day of the month, and the lines are numbered in sequence, increasing in one direction. A pointer to be described, travels in close relation to the scales 57.

An operating gear 58 is mounted centrally upon the platform 55 and is rigidly attached thereto by screws 59 or the like, to move bodily with the carriage about the orbit gear. This operating gear is provided with a hub 60 to slidably receive the upper portion of the shaft 54. The upper end of this shaft projects upwardly beyond the hub 60 and is provided with a reduced extension 61, formed square in cross section, thereby having parallel faces. A frame 62 is mounted upon the hub 60 of the operating gear 58, and this frame embodies a lower plate 63, having reinforcing stiffening ribs 64. The plate is provided centrally thereof with a depending socket 64', having a bore square in cross section to receive the square end 61 of the shaft. The plate 63, therefore, remains fixed with relation to the shaft 54, during its travel around the orbit gear. The frame 62 further embodies an upper plate 65, which is rigidly connected with the lower plate by rods 66, preferably four in number. These rods have their ends screw-threaded for receiving nuts 67, arranged above and below the plates, the rods passing through openings in the plates, as is obvious. By proper manipulation of the nuts 67 engaging the upper plate 65, this upper plate may be inclined with respect to the carriage, for a purpose to be explained.

The numeral 68 designates the earth or globe, which is carried by an upstanding rod 69 and rotates with this rod. The rod extends through the axis of rotation of the globe and is arranged at the proper inclination for illustrating the inclination of the earth upon its axis. The globe-carrying rod 69 has its lower end rotatably mounted in openings 70, formed in the ends of the inclined portions 71 of brackets 72. These brackets have vertical portion 73, which extend through openings 74 in the upper plate 65 and hence have no connection with this plate. The lower ends of the vertical portions 73 extend through openings in the lower plate 63 and carry nuts 75, arranged above

and below the plate 63, for clamping engagement therewith. The brackets 72 are disposed in the plane of the inclined globe carrying rod 69, and remain in this plane throughout their travel about the orbit gear. By virtue of this arrangement, the fixed inclination of the earth's axis, due north and south, is maintained as the globe travels about the orbit gear. A flexible shaft 76 is attached to the lower end of the globe carrying rod 69 to rotate the same, and this flexible shaft extends through an opening 77 in the upper plate 65. The flexible shaft is connected with suitable gearing in turn driven by the operating gear 58, in such a manner that the globe is rotated upon its axis, and will make the proper number of revolutions for its complete travel throughout its orbit, simulating the rotation and travel of the earth.

A gear frame 78 is rigidly mounted upon one end of the lower plate 63, and embodies spaced superposed horizontal plates 79, connected by vertical rods 80. A gear 81 is mounted upon a vertical shaft 82, attached to the lower end of the flexible shaft 76. The shaft 82 is journaled in a bearing 83 and an opening formed in a bracket 84, attached to the upper plate 79. The gear 81 is held against longitudinal movement and engages a larger gear 85. Gears 81 and 85 preferably have a ratio of 1—2. The gear 85 is rigidly mounted upon a vertical shaft 86, suitably journaled in bearings carried by the two upper plates 79. The vertical shaft 86 has a gear 87 rigidly secured to its lower end, engaging a larger gear 88. The gears 87 and 88 preferably have a ratio of 1—3. The gear 88 is rigidly mounted upon a vertical shaft 89, journaled in suitable openings formed in the two upper plates 79 and a smaller gear 90 is rigidly attached to the lower end of the vertical shaft 89 and engages a larger gear 91. Gears 90 and 91 preferably have a ratio of 1—6. Gear 91 is rigidly mounted upon a vertical shaft 92, journaled in bearings formed in the two lower plates 79, and a gear 93 is rigidly mounted upon the lower end of the vertical shaft 92. Gear 93 is in permanent engagement with the operating gear 58, and these gears preferably have a ratio of 1—10 $\frac{1}{6}$. It is thus seen that as the frame is traveling with the carriage in its orbit about the orbit gear 89, the frame having its longitudinal axis maintained due north and south, while the radial position of the wheeled carriage is constantly changing, there is a relative turning movement between the operating gear 58 and the gear 93, causing the train of gears embodying this gear 93 to turn and this turning movement is transmitted to the rod 69, rotating the earth upon its axis. The gearing is of such a character that the globe makes a complete revolution for each day.

The lower plate 63 is provided with a pointer 94, traveling in proximity to the edge of the platform 55 for co-action with the month scales 57. Thus as the pointer indicates the movement of the earth in its orbit for one day, the globe 68 will be turned for one complete revolution.

Means are provided for supporting a moon in proper spaced relation from the earth and moving the same bodily around the earth. This means includes a generally inverted U-shaped bracket 95, having vertical legs 96, which are rigidly attached at their lower ends to the upper plate 65 of the supporting frame, adjacent to the periphery of this upper plate, which is preferably circular. Co-acting with this supporting bracket is an inverted generally L-shaped supporting rod 97, having a vertical portion 98 and a horizontal portion or arm 99. The lower end of the vertical portion 98 is pivotally connected with an endless chain 100 preferably in the form of a sprocket chain. The horizontal arm 99 is pivotally connected with the horizontal portion 95, as shown at 101, to rotate horizontally with relation to the supporting bracket, the supporting rod 97 turning within the supporting bracket. At its free end, the arm 99 is preferably provided with a hook 102 for receiving the eye formed upon the end of a depending link 103 carrying a moon 104 rigidly attached thereto. Both the moon and earth may have their surfaces painted or otherwise formed for indicating the surfaces of the earth and moon. The horizontal arm 99 supports the moon at a suitable distance from the earth 68 and causes the moon to travel about the earth, making a complete movement in its orbit, each lunar month. The upper plate 65, see particularly Figures 1, 3 and 5, is provided with an upstanding annular flange 105 and a depending annular flange 106, integral therewith. These flanges serve to stiffen and reinforce the upper plate, and the upper flange 105 serves as a guide for the endless sprocket chain 100. A portion of the upper flange 105 is cut away, providing a space 107, spanned by the sprocket chain 100 and the sprocket chain at this space engages a sprocket wheel 108. A lever 109 is pivoted to the upper plate 65, at 110, and carries a roller 111, engaging with the sprocket chain 100. A retractile coil spring 112 is connected with the lever and may be attached to one of the brackets 71 and serves to swing the lever 109 inwardly, thereby maintaining the sprocket chain suitably taut, and in permanent engagement with the sprocket wheel 108. The sprocket wheel 108, see Figure 3 particularly, is rigidly mounted upon a vertical shaft 113, and this shaft is journaled in openings formed in horizontal plates 114, included in a gear frame, rigidly attached to the lower plate 63 diametrically opposite the

first named gear frame. The shaft 113, Figure 6, has a small gear 115, rigidly attached thereto, and engaging a larger gear 116, rigidly secured to the vertical shaft 117. These gears preferably have a ratio of 1—6. The shaft 117 is journaled in openings formed in the plates 114 and this shaft extends downwardly below the lower plate 63 and has a gear 118 rigidly attached thereto, engaging the operating gear 58. These gears preferably have a ratio of 1—11 $\frac{1}{6}$. It is obvious that the relative turning movement between the operating gear 58 and the supporting frame including the plate 63 will drive the train of gears including the gear 118 and this train of gears turn the sprocket wheel 108, effecting the travel of the endless sprocket chain. The gearing, including the gears 118 is of such a ratio or character that the moon is caused to travel completely throughout its orbit about the earth in a lunar month, or as nearly so as practical.

The plane of the orbit of the earth is regarded as fixed, while the plane of the orbit of the moon is inclined with respect to the plane of the orbit of the earth. In order that the proper relative inclination may be effected between the plane of the orbit of the moon and that of the earth, means have been provided to angularly adjust or tilt the upper plate 65, constituting the sole support for the moon supporting means, without disturbing the inclination of the lower plate 63, which carries the earth supporting means. This adjustment of the inclination of the upper plate 65 is effected by adjusting the nuts upon the upper ends of the rods 66, as explained. The eclipse of the sun occurs when the moon travels between the earth and the sun and the planes of the orbits of the moon and earth intersect. By angularly adjusting or changing the inclination of the upper plate, the inclination of the orbit of the moon may be varied so that an eclipse of the sun may be produced at any selected time. If it is desired to produce the effect of an eclipse of the sun in April or October, the side of the upper plate, adjacent to July of the scale upon the platform 55, is raised and the opposite side near January is lowered the same distance, whereby the segments at April and October are at the same elevation.

The operation of the apparatus is as follows:

In Figure 1 of the drawings, the pointer 94 is adjacent to the scale at the June segment. The inclination of the axis of rotation of the earth 68 is now such that the rays of light from the sun pass more directly upon the upper portion of the earth. This position of the earth with respect to the sun illustrates the rays of light from the sun shining principally upon the upper portion of the earth, producing practically six months of day at the North Pole and six months of night at

the South Pole, during the summer months and vice versa during the winter months. The operator now turns the crank 28 clockwise at a suitably slow speed and the vertical shaft 22 is rotated, causing the radial shaft 31 to travel circumferentially of the orbit gear 38. This movement of the shaft 31 effects the orbit travel of the carriage 41. During this orbit travel of the carriage, such carriage is constantly changing its radial position, while the longitudinal axis of the supporting frame, including the plate 63, remains constant, due north and south. This is effected by the rotation of the gear 51 by the orbit gear 38. The gear 51 through the medium of gear 52 rotates gear 53 in an opposite direction, and the ratio between gears 51 and 38 and gears 53 and 52 is the same, as explained. The constant shifting of the radial position of the platform 55 of the wheel carriage with relation to the plate 63 and the supporting frame, effects a relative turning movement between the operating gear 58 and the supporting frame including the plate 63. Hence, gear 93 is driven by the operating gear 58 and through the medium of the train of gears connected therewith, rotates the earth carrying rod 69, causing the earth to make 365 complete revolutions upon its longitudinal axis during the time that it completes its travel throughout its orbit. The earth, therefore, makes a complete revolution upon its axis for each day. In a similar manner, the gear 118 is rotated by the gear 58, and through the medium of the associated train of gears, and endless sprocket chain, the moon completes its travel through its orbit about the earth in a lunar month. As the pointer 94 reaches each month segment, the relative position of the earth to the sun is effected and the light projected upon the earth from the lamp 34, showing just how the light strikes the earth in each month. The action of the moon is also clearly indicated by the apparatus, and as the moon travels in its orbit about the earth, the various changes or phases of the moon are clearly visible, due to the action of the light projected upon the earth and moon. The eclipse of the sun is produced when the moon passes between the source of light and the earth, and the eclipse of the moon is produced when the earth passes between the sun and the moon. The apparatus is, therefore, capable of demonstrating in a simple and reliable manner the various actions of the earth and moon, with respect to the sun.

It is to be understood that the form of my invention, herewith shown and described, is to be taken as a preferred example of the same, and that various changes in the shape, size and arrangement of parts, may be resorted to, without departing from the spirit of my invention, or the scope of the subjoined claims.

Having thus described my invention, I claim:

1. In a tellurian of the character described, a support, an earth element, supporting means for the earth element mounted upon the support, a second support arranged above the first support and connected therewith, a moon element, supporting means for the moon element to cause the same to travel in an orbit about the earth element, the last named supporting means being mounted upon the second support, and means whereby the second support may be inclined with relation to the first support for varying the inclination of the orbit of the moon with respect to the orbit of the earth element.

2. In a tellurian of the character described, a generally horizontal support, an upstanding rotatable shaft mounted upon the support and terminating near the upper surface of the same, a stationary orbit gear mounted upon the support and surrounding the rotatable shaft, a wheeled carriage arranged upon the support outwardly of the orbit gear to travel circumferentially of the orbit gear and also capable of radial movements with relation to the rotatable shaft, radially adjustable connecting means between the rotatable shaft and carriage and serving to cause the carriage to travel circumferentially of the orbit gear upon the turning movement of the shaft, a spring connected with the carriage and drawing the same toward the shaft, gearing mounted upon the carriage to move bodily therewith and including a pair of gears rotating upon their axes with relation to the carriage and in opposite directions with relation to each other, one gear being held in permanent engagement with the orbit gear by the action of the spring, an upstanding shaft mounted upon the carriage and secured to the other gear in said pair and rotatable upon its axis with relation to the carriage, a supporting frame having a socket detachably mounted upon the upper end of the upstanding shaft and turning with such shaft, an operating gear arranged between the supporting frame and carriage and rigidly attached to the carriage, gearing bodily mounted upon the supporting frame and including a gear engaging the operating gear and adapted to be separated therefrom when the supporting frame is removed from the upstanding shaft, a rotatable inclined rod arranged above the supporting frame, an earth element carried by the rod, means for supporting the inclined rod and bodily mounted upon the supporting frame, a flexible driving connection between the second-named gearing and the inclined rotatable shaft, and a source of light for coaction with the earth element.

3. In a tellurian of the character described, a generally horizontal support, a rotatable element mounted upon the support and having its axis of rotation generally vertical, an elliptical orbit gear rigidly attached to the support and surrounding the rotatable element, a wheeled carriage arranged upon the support outwardly of the orbit gear, longitudinally adjustable connecting means between the rotatable element and carriage, a spring to draw the carriage inwardly toward the rotatable element, gearing bodily mounted upon the carriage and including a pair of gears rotatable upon their axes in opposite directions with relation to each other, one gear being held in engagement with the orbit gear by the spring, an upstanding shaft mounted upon the carriage and rotatable with relation thereto and secured to the other gear in said pair for turning movement there-

with, a supporting frame arranged near and above the carriage and attached to the upstanding shaft and turning with such shaft, an operating gear arranged between the supporting frame and carriage and rigidly attached to the carriage, gearing bodily mounted upon the supporting frame and including a gear engaging the operating gear, a rotatable inclined rod arranged above the supporting frame, an earth element carried by the rod, means for supporting the inclined rod and bodily mounted upon the supporting frame, a flexible driving connection between the second-named gearing and the inclined rotatable rod, and a source of light for coaction with the earth element.

5. In a tellurian of the character described, a generally horizontal support, a rotatable element mounted upon the support and having its axis of rotation generally vertical, an elliptical orbit gear rigidly attached to the support and surrounding the rotatable element, a wheeled carriage traveling upon the support outwardly of the orbit gear, longitudinally adjustable connecting means between the rotatable element and carriage, a spring to draw the carriage inwardly toward the rotatable element, gearing bodily mounted upon the carriage and including a pair of gears rotatable upon their axes in opposite directions with relation to each other, one gear being held in engagement with the orbit gear by the spring, an upstanding shaft mounted upon the carriage and rotatable with relation thereto and secured to the other gear in said pair for turning movement therewith, a horizontal supporting member arranged near and above the carriage and attached to the upstanding shaft to turn therewith, an operating gear arranged between the carriage and supporting member and rigidly attached to the carriage, gearing bodily mounted upon the generally horizontal supporting member and driven by the operating gear, an inclined rotatable rod arranged above the supporting member, an earth element carried by the inclined rod, means for supporting the inclined rod and mounted upon the supporting member, a driving connection between the inclined rod and second-named gearing, and a source of light for coaction with the earth element.

6. In a tellurian of the character described, a generally horizontal support, a rotatable element mounted upon the support and having its axis of rotation generally vertical, an elliptical orbit gear rigidly attached to the support and surrounding the rotatable element, a wheeled carriage to travel upon the support, longitudinally adjustable connecting means between the rotatable element and carriage, a spring to draw the carriage inwardly toward the rotatable element, a supporting frame mounted upon the carriage to travel bodily therewith and to turn upon its

vertical axis with relation thereto, gearing mounted upon the carriage and connected with the supporting frame to turn the same upon its axis of rotation in an opposite direction to the direction of travel of the carriage and including a gear held in engagement with the orbit gear by the spring, an operating gear mounted upon the carriage and stationary with relation thereto, gearing mounted upon the supporting frame and engaging the operating gear, an inclined rotatable rod extending above the supporting frame and mounted upon the same and connected with the second-named gearing to be driven thereby, an earth element mounted upon the inclined rod, and a source of light for coaction with the earth element.

7. In a tellurian of the character described, a generally horizontal support, a rotatable element mounted upon the support, an orbit gear rigidly attached to the support and surrounding the rotatable element, a wheeled carriage to travel upon the support, connecting means between the rotatable element and carriage so that they travel together, a supporting frame mounted upon the carriage and embodying spaced upper and lower generally horizontal plates, gearing mounted upon the carriage and connected with the lower plate to turn the same upon its vertical axis in an opposite direction to the travel of the carriage and including a gear engaging the orbit gear, an operating gear mounted upon the carriage to turn therewith, gearing mounted upon the supporting frame and engaging the operating gear, an inclined rotatable rod extending above the supporting frame and mounted thereon and connected with the second-named gearing to be driven thereby, an earth element mounted upon the inclined rod, a curved guide element carried by the upper plate of the supporting frame, an endless flexible element engaging the curved guide element, gearing mounted upon the supporting frame and driven by the operating gear and driving the endless flexible element, a supporting element connected with the endless flexible element, a moon element carried by the supporting element, and a source of light to coact with the earth element.

8. In a tellurian of the character described, a generally horizontal support, a rotatable element mounted upon the support, a stationary orbit gear surrounding the rotatable element, a wheeled carriage to travel upon the support, connecting means between the rotatable element and carriage, a supporting frame mounted upon the carriage and embodying upper and lower generally horizontal plates, gearing mounted upon the carriage and connected with the lower plate to turn the same upon its vertical axis in an opposite direction to the travel of the carriage and including a gear engaging the orbit gear,

- an operating gear rigidly mounted upon the carriage, gearing mounted upon the supporting frame between the upper and lower plates and engaging the operating gear, an inclined rotatable rod extending above the supporting frame, means mounted upon the lower plate and holding the inclined rod, an earth element mounted upon the inclined rod, a curved guide element carried by the upper plate, an endless sprocket chain engaging the curved guide element, gearing mounted upon the supporting frame between the upper and lower plates and driven by the operating gear and including a sprocket wheel engaging 10 the sprocket chain, a supporting element connected with the sprocket chain to be moved thereby, a moon element carried by the supporting element, and a source of light to coact with the earth element.
- 15 9. In a tellurian of the character described, a generally horizontal support, a rotatable element mounted upon the support, an orbit gear rigidly attached to the support, a wheeled carriage to travel upon the support, 20 connecting means between the rotatable element and carriage, a supporting frame mounted upon the carriage and embodying upper and lower generally horizontal plates, means whereby the upper plate may be adjusted to vary its inclination with relation to the lower plate, gearing mounted upon the carriage and connected with the lower plate to turn the same upon its vertical axis in an opposite direction to the travel of the carriage and including a gear engaging the orbit gear, an operating gear mounted upon the carriage to turn therewith, gearing mounted 25 upon the supporting frame and engaging the operating gear, an inclined rotatable rod extending above the supporting frame, an earth element carried by the rod, an upstanding support carried by the lower plate and free from connection with the upper plate and having a bearing holding the inclined rotatable rod, means whereby the rod is rotated by the second-named gearing, a curved guide element carried by the upper plate, an endless flexible element engaging the curved guide element, gearing mounted upon the 30 supporting frame and driven by the operating gear and driving the endless flexible element, a supporting element mounted upon the upper plate to turn therewith, an upstanding rod attached to the endless flexible element and having a horizontal extension pivotally connected with the supporting element, a moon element carried by the horizontal extension, and a source of light coacting with the earth element.
- 35 10. In a tellurian of the character described, a support, means to cause the support to travel in an orbit about a fixed point, a supporting frame mounted upon the support, means to turn the supporting frame upon its vertical axis in a direction opposite to the 35
- direction of travel of the support, said supporting frame including upper and lower horizontal plates, an inclined rod arranged above the supporting frame, means mounted upon the supporting frame for holding the 70 rod, means to rotate the rod, an earth element mounted upon the rod, a curved guide carried by the upper plate, a flexible endless element engaging the guide, means to drive the flexible endless element, a supporting element 75 connected with the endless flexible element to be moved thereby, a moon element carried by the supporting element, and a source of light for coaction with the earth element.
